(57) **CLAIM**

I claim the ornamental design of a housing for a gate valve, as
shown and described.

DESCRIPTION

FIG. 1 is a perspective end view of a gate valve housing for
pressure or suction hose lines.

FIG. 2 is a perspective view of one side of the gate valve
housing of FIG. 1.

FIG. 3 is a perspective view of an opposite side of the gate
valve housing of FIG. 1.

FIG. 4 is a side view of the side of the gate valve housing
shown in FIG. 2.

FIG. 5 is a side view of the side of the gate valve housing
shown in FIG. 3.

FIG. 6 is an end view of the gate valve housing of FIG. 1.

FIG. 7 is a bottom view of the gate valve housing of FIG. 1;
and,

FIG. 8 is a top view of the gate valve housing of FIG. 1.
